UNITED STATES PATENT OFFICE.

GEORGE THOMAS BUCKHAM, OF WESTMINSTER, LONDON, ENGLAND, ASSIGNOR TO
VICKERS LIMITED, OF WESTMINSTER, ENGLAND.

AUTOMATIC GUN.

1,262,169.

Specification of Letters Patent.

Patented Apr. 9, 1918.

Application filed June 8, 1916. Serial No. 102,435.

To all whom it may concern:

Be it known that I, GEORGE THOMAS BUCKHAM, a subject of the King of Great Britain, residing at Vickers House, Broadway, Westminster, in the county of London, England, have invented certain new and useful Improvements in or Relating to Automatic Guns, of which the following is a specification.

10 This invention relates to automatic guns of the kind in which the lock is operated by toggle levers comprising a crank and a side lever. In such guns it is usual, through the intermediary of an arm on the tumbler 15 operating with the said side lever, to cock the striker during the bending of the toggle levers (whether the gun is operated manually or automatically) the tumbler in such case being angularly displaced to force the striker 20 to its rearmost position past the safety sear bent just as the crank is passing the vertical position. This action, owing to the return movement of the crank to the vertical position, again retracts the striker, temporarily 25 removing it from the safety sear bent and causing what is known as recocking. This recocking of the striker is disadvantageous as it results in an undue weakening of the 30 striker spring, and also results in a lack of smoothness in the working of the mechanism; the chief object of the invention is to provide improved means whereby the striker will be cocked during the rearward movement of the lock but will not be retracted 35 during the forward movement of the lock so as to avoid the aforesaid recocking of the striker.

According to the invention, the cover of 40 the gun mechanism casing is provided with a tripping piece against which the tumbler comes during the rearward travel of the lock, to displace the tumbler and cock the striker, the said tumbler having an arm by which it can also be displaced by the side 45 lever to cock the striker in the usual manner when the lock is operated by hand with the cover open. The tumbler may be provided with an upwardly projecting extension for engagement with the aforesaid tripping 50 piece on the cover.

In order that the said invention may be clearly understood and readily carried into effect I will describe the same more fully

with reference to the accompanying drawing, in which:

Figures 1 and 2 are sectional side elevations showing the lock mechanism of an automatic gun provided with a constructional form of my improvements, Fig. 1 showing the parts in the position they occupy when the barrel has partly recoiled and Fig. 2 showing the position they occupy when the barrel has fully recoiled. Fig. 3 is a plan of the lock mechanism (with the cover of the mechanism casing removed) 60 showing the position of the parts when the barrel and the lock are in the forward or firing position; and Fig. 4 is a section taken approximately on the line X, X of Fig. 1 looking in a forward direction, the cover 65 of the mechanism casing being shown in full lines in its closed position and in broken lines in its open position. Figs. 5, 6 and 7 are diagrammatic views showing the position of the lever, which moves the cartridge carrier downwardly, with relation to the side cams and the cartridge carrier, the parts being shown with the barrel in fully 70 recoiled position, the barrel returning after 75 recoiling and the barrel approaching its forward position.

A is the lock, A' the crank, 1, the recoiling barrel, 2, the cartridge carrier movably mounted in the lock A, and A³ the side lever. The crank A' is pivotally connected by the 85 shaft C² to an extension 3 on the barrel, and the side lever A³ is connected at one end to the crank, and at the other end to the lock. 4, 4 are the side cams which coöperate with 80 horns on the cartridge carrier 2. B is the tumbler, B' the striker, B² the safety sear and B³ the trigger sear. C is the mechanism casing cover and C' is the tripping piece 90 thereon with which an extension b on the tumbler engages during the rearward movement of the lock, to cock the striker.

As shown in the drawings, the crank A' has two downward extensions C¹² carrying rollers C¹², which, during the initial carrying movement of the barrel, coöperate with 100 fixed inclines b'' arranged on the side plates of the mechanism casing. These inclines terminate at their rear in straight guides b'x for the rollers. The stops b' for coöperating with the projection c'' on the crank A¹ 105 may be in the form of spring-controlled

plungers, as shown in Fig. 1 of the drawing. After the toggle joint has been initially bent by the cooperation of the inclines b'' with the rollers C^x , the continuous rearward movement of the crank shaft C^2 carries the projections c'' into contact with the beveled faces on the spring plungers b^x , which plungers are displaced against the resistance of their springs to enable the projections c'' to pass behind them. On the forward movement of the barrel taking place under the influence of its return spring (not shown), the front faces of the projections c'' coöperate with the rear faces of the plungers b^x without lifting the latter, and the barrel moves forward without the lock A, the crank A' being further angularly displaced. At the same time, the aforesaid side cams 4, 4 carried by the barrel extension move clear of the horns on the carrier, which is then moved downwardly by levers 5 pivoted to the mechanism casing and controlled by the cam surfaces 6 on the cams 4, 4. The front faces of the projections c'' coöperate with the rear faces of the plungers b^x without lifting the latter, and the barrel moves forward without the lock A, the crank A' being further angularly displaced. At the same time, the aforesaid cams 4, 4, upon which the horns 7 on the carrier have been resting (see Figs. 5-7), move clear of these horns, and the carrier is then moved downwardly by the levers 5, which, as aforesaid, are pivoted to the mechanism casing and controlled by the cam surfaces 6 on the side cams 4, 4. The crank A' is also formed with arms 8 which coöperate with the straight portions b'^x of the inclines on the side plates 40 of the mechanism casing to prevent overthrow of the crank. When the projections c'' move clear of the plungers b^x (Fig. 1), the spiral spring inclosed in the casing C^x causes the crank A' to move the lock toward its forward position by the straightening of the toggle levers.

The mechanism casing carries the spring-controlled pivoted pawl 9 which, in the event of the recoil movement of the barrel 50 being insufficient to enable the horns of the carrier 2 to become clear of the cams 4, 4, will lie in the path of the upper portion of the carrier, and thus prevent the lock from being moved forward, thereby avoiding the possibility of the cartridge in the belt being fired by the impact with them of the nose of the cartridge in the carrier.

The shaft C^2 of the crank is provided with a handle C^{2x} , by means of which the 60 breech mechanism can be moved into the open position by hand; in this event, as the side cams 4, 4 for controlling the carrier are attached to the barrel extension, which is then stationary, the improved mechanism 65 operates in substantially the same manner

as that of the automatic guns at present in use when operated by hand.

When the lock A is moved rearward automatically a roller on the arm b comes against the aforesaid tripping piece C', and is thereby displaced into the position shown by Fig. 1, to retract the striker B' into engagement first with the trigger sear B³ and then immediately afterward with the safety sear B². When this operation has been completed the roller on the arm b moves clear of the tripping piece C' and the tumbler is then moved by its spring into the position shown by Fig. 2. During the forward movement of the barrel the roller on the arm b displaces the tripping piece C' against the resistance of a spring and as the crank A' and the side lever A³ resume their straightened position the said side lever disengages the safety sear B² from the striker 80 because of the fact that the portion 10 engages the end 11 of the safety sear to move the latter downwardly as is well understood and permits the striker to advance slightly until arrested by the trigger sear B³. In 90 Fig. 1, the maximum angle reached by the side lever is indicated by chain lines and from this it will be seen that this side lever does not operate upon the tumbler. A similar action to that described above occurs 95 when the lock is operated by hand instead of automatically. It will therefore be obvious that so long as the cover is not opened the cocking of the striker will be effected by the tumbler coöperating with the tripping 100 piece, whether the gun be operated automatically or manually.

When however, the lock is being operated by hand with the cover raised the aforesaid tripping piece C' is not available to operate the tumbler B which is then displaced to cock the striker by the side lever A³ through the intermediary of the arm b' on the tumbler, the parts being so constructed and arranged that the striker will be retracted only sufficiently to enable the trigger sear B³ to engage with its bent on the striker, and therefore not sufficiently to enable the safety sear B² to engage with its bent.

The means for actuating the trigger sear B³ to release the striker comprises a pivoted member B⁴, which is adapted to engage with the said sear. This pivoted member, when the parts are moved forward, or into their firing positions, bears against a projection 12 on the casing of the mechanism. Thus, the trigger will be actuated at the proper time.

What I claim and desire to secure by Letters Patent of the United States is:—

1. In an automatic gun, the combination of the mechanism casing, its movable cover, the lock, the toggle levers for operating the lock, the striker, means for cocking said 130

striker during the manual operation of the lock when the movable cover is open, and means carried by said cover for cocking said striker when the cover is closed.

5 2. In an automatic gun, the combination of the mechanism casing, its movable cover, the lock, the toggle levers for operating the lock, the striker, the tumbler which cocks said striker during the manual operation of 10 the lock with the movable cover open and which has an arm bearing against one of the toggle levers, and a tripping piece which is mounted on said movable cover and serves to displace the tumbler and cock the striker 15 during the rearward movement of the lock when said cover is closed.

3. In an automatic gun, the combination of the mechanism casing, its movable cover, the lock, the barrel extension, the operating 20 crank pivoted to said extension, the side lever, the striker, the tumbler which cocks said striker during the manual operation of the lock with the movable cover open and which has an arm bearing against said side lever, and a tripping piece which is mounted 25 on said movable cover and serves to displace

the tumbler and cock the striker during the rearward movement of the lock when said cover is closed.

4. In an automatic gun, the combination 30 of the mechanism casing, its movable cover, the lock, the barrel extension, the operating crank pivoted to said extension, the side lever, the striker, the safety sear and the trigger sear for engaging with said striker, the 35 tumbler which cocks said striker into engagement with the trigger sear during the manual operation of the lock with the movable cover open and which has an arm bearing against said side lever, and a tripping piece which is mounted on said movable cover and serves to displace the tumbler and cock the striker into engagement with the safety sear during the rearward movement 40 of the lock when said cover is closed. 45

In testimony whereof I affix my signature in the presence of two witnesses.

GEORGE THOMAS BUCKHAM.
